UNITED STATES PATENT OFFICE.

CHARLES W. CROGAN, OF BANGOR, MAINE.

TAPELINE CASE STRUCTURE.

Application filed December 1, 1919. Serial No. 341,607.

To all whom it may concern:

Be it known that I, CHARLES W. CROGAN, a citizen of the United States, residing at Bangor, in the county of Penobscot and

5 State of Maine, have invented certain new and useful Improvements in Tapeline Case Structures, of which the following is a specification.

This invention relates to improvements in 10 the case structures of tape lines of the type disclosed in Patents Numbers 1,216,418 and 1,233,034, dated February 20, 1917, and July 10, 1917, respectively, and the present invention has for its object to generally improve 15 and simplify the structure of the case to provide for its economical manufacture.

Another and more specific object of the invention is the provision of a case for this type of tape lines consisting essentially of 20 two sections or parts each constructed or stamped from a single blank of sheet metal and assembled in such manner as to efficiently house and guide the tape line and to exert sufficient pressure thereon to prevent 25 its loose movement and accidental slipping.

With these and other objects in view as will appear as the description proceeds the invention comprises the novel features of construction combination of elements and 30 arrangement of parts which will be more fully described in the following specification and set forth with particularity in the claims appended hereto.

Figure 1 represents a side elevation of the 35 improved case structure.

Figure 2 represents an edge elevation thereof.

Figure 3 is a section taken on the line 3—3 of Fig. 2.

40 Figure 4 is an interior elevation of one section of the casing showing the parts of the winding mechanism as arranged therein.

Figure 5 represents a sectional view on the line 5—5 of Figure 1.

45 Figure 6 represents a reduced plan view of the blank of sheet metal from which one part or section of the case is constructed.

Referring to the drawing, wherein similar 50 reference numerals designate corresponding parts throughout the several views, the numerals 5 and 6 indicate the parts or sections of the case which, when properly assembled form a housing for the tape line and parts associated therewith. The case is of the improved shape as disclosed in my two prior 55 patents above referred to and the part or

section 5 consists of the side wall 7 and flange 8 formed integral therewith and directed at right angles thereto. The flange 8 is substantially semi-circular and is formed 60 integral with an elongated tongue or extension 9 which, after the flange 8 is turned at right angles to the side wall or body portion 7 is properly curved to extend across side face of the V-shaped portion of the side wall 65 inwardly of the apex thereof as shown in Fig. 3. The terminal of the extension 9 is provided along one of its longitudinal edges with a recess 10 and the opposite longitudinal edge of the adjacent terminal of the 70 curved flange 8 is formed with a corresponding recess 11. The recessed terminals of the flange and extension are interfitted, as suggested in Figure 5 and the terminal of the curved flanged portion 8 is subsequently 75 turned back as indicated at 12 in Figure 3 so as to securely interlock the flange and extension thereby maintaining the latter in predetermined position with relation to the side wall 7.

The other case section 6 includes a body portion 13 constituting one of the side walls of the case and a right angularly directed flange 14 which constitute the rim of the casing and is extended entirely about the 85 section and of such size as to receive the flange 8 of the section 5, when the sections are properly assembled. When the sections of the case are assembled, they are permanently secured together as by brazing, welding, or soldering, or otherwise connecting the flanges 8 and 14 one to the other. The flange 14 is provided with a transverse opening 15 through which the tape line 16 extends and at a point substantially diametrically opposite the opening 15 the flange 8 of the section 5 is formed with a substantially U-shaped slit 17 through which the tape line 16 extends from the rotatable supporting drum or reel 18 into the space provided 90 between portions of the flanges 8 and 14 the tongue 17^a defined by the slit 17 being turned inwardly, as in Fig. 3, to properly guide the tape line 16.

That portion of the flange 8 and the extension 9 over which the tape line 16 extends prior to its passage through the opening 15 is spaced from the flange 14 throughout the major portion of its length while a series of transverse ribs 19 is formed on the flange 8 105 and produces sufficient friction by contact with the tape to prevent excessive loose 110

movement and slipping thereof while by maintaining the major portion of the flange in spaced relation to the outer flange 14 possibility of injuring or binding the tape line 5 incident to denting or bending the flange 14 is eliminated.

A locking cam 20 is pivotally mounted in the tape line case between the side walls thereof at a point adjacent the outlet opening 15 for the tape line and is so arranged as to bear against the terminal portion of the extension 9 and thus frictionally clamp the tape line 16 between that portion of the extension or guide 9 and the contiguous portion 10 of the inner surface of the outer flange 14 thereby preventing withdrawal of the tape line from the case. Externally of the tape line case an adjusting arm 21 is secured to one of the pivot pins of the cam or eccentric 15 20 25 30 35 40 45 50 55 60 65 70 75 80 85 90 95 100 105 110 115 120 125 130

At a point substantially diametrically opposite the outlet opening 15 for the tape line, the outer flange 14 is provided with an elongated opening 22 Fig. 2 having a pointer or indicator 23 formed along one of its longitudinal edges under which the exposed portion of the tape line 16 is movable to indicate the length of the tape line 30 which is withdrawn from the case. It is to be here noted that the opposite side walls 7 and 13 of the casing are preferably provided with inwardly directed depressions of similar configuration or outline to that of the casing proper, as is indicated at 7' and 13' respectively.

What I claim is:

1. In a tape measure, a case including side walls and interfitting inner and outer flanges 40 thereon, an extension carried by the inner flange extending across the interior of the case and constituting a guide for a flexible tape line, and a series of spacing elements 45 formed on the inner flange and extension for maintaining the flexible tape line in contact with portions of the case flanges.

2. In a tape measure, a two part case, a marginal flange carried by one part, a segmental internal flange carried by the second 50 part and secured to said marginal flange, an elongated extension carried by one terminal of the segmental flange and having its outer terminal connected with the opposite terminal of the segmental flange.

3. In a tape measure, a two part case, an angularly directed flange carried by one part of the case, an internal segmental flange carried by the second case part having one terminal hooked and an elongated extension 55 carried by the opposite terminal of the segmental flange having its terminal interlocked with the hooked terminal of the flange.

4. A tape measure comprising a two part case for receiving a windable tape line, each

of said parts formed with a flange, one of said flanges being continuous and constituting the rim of the case and further enclosing and abutting the other flange, and an integral flexible extension on said other 70 flange projecting from one end and interfitting with the other end of said enclosed flange to provide a support for the tape line, said extension opposing and spaced from said rim to accommodate the tape line between the extension and the rim flange. 75

5. A tape measure comprising a two part case for receiving a windable tape line, each of said parts formed with a flange, one of said flanges being continuous and constituting the rim of the case and further enclosing and abutting against the other flange, and an integral flexible extension on said other flange projecting from one end and interfitting with the other end of said enclosed 80 flange to provide a support for the tape line, said extension opposing and spaced from said rim to accommodate the tape line between the extension and the rim flange, said rim flange having one portion thereof circular in contour and its remaining portion angle-shaped, that part of said extension opposing the circular portion of the rim flange being arranged closer thereto than a part of the extension which opposes a 95 part of the angle shaped portion of the rim flange.

6. A tape measure comprising a two part case for receiving a windable tape line, each of said parts formed with a flange, one of 100 said flanges being continuous and constituting the rim of the case and further enclosing and abutting against the other flange, and an integral flexible extension on said other 105 flange projecting from one end and interfitting with the other end of said enclosed flange to provide a support for the tape line, said extension opposing and spaced from said rim to accommodate the tape line between the extension and the rim flange, said rim flange having one portion thereof circular in contour and its remaining portion angle-shaped, that part of said extension opposing the circular portion of the rim flange being arranged closer thereto than a 110 part of the extension which opposes a part of the angle shaped portion of the rim flange, said circular portion of said rim flange having one terminus provided with an opening for the passage of the tape line 115 from the case, and said extension in proximity to its integral end formed with a slit for the passage of the tape line into the space formed between the extension and the rim flange, 120

7. A tape measure comprising a two part case for receiving a windable tape line, each of said parts formed with a flange, one of said flanges being continuous and constituting the rim of the case and further enclos- 130

- ing and abutting against the other flange, and an integral flexible extension on said other flange projecting from one end and interfitting with the other end of said enclosed flange to provide a support for the tape line, said extension opposing and spaced from said rim to accommodate the tape line between the extension and the rim flange, said flange provided at a point in proximity to the interfitting end of said extension with an opening for the passage of the tape line from the case, and said extension in proximity to its integral end formed with a slit for the passage of the tape line into the space formed between the extension and the rim flange.
8. A tape measure comprising a two part case for receiving a windable tape line, each of said parts formed with a flange, one of said flanges being continuous and constituting the rim of the case and further enclosing and abutting against the other flange, and in integral flexible extension on said other flange projecting from one end and interfitting with the other end of said enclosed flange to provide a support for the tape line, said extension opposing and spaced from said rim to accommodate the tape line between the extension and the rim flange, said rim flange having one portion thereof circular in contour and its remaining portion angle-shaped, that part of said extension opposing the circular portion of the rim flange being arranged closer thereto than a part of the extension which opposes a part of the angle shaped portion of the rim flange, said circular portion of said rim flange having one terminus provided with an opening for the passage of the tape line from the case, and said extension in proximity to its integral end formed with a slit for the passage of the tape line into the space formed between the extension and the rim flange, and said extension provided with means for maintaining a part of the outer convolution of the tape line in contact with the circular portion of the rim flange and further having means for maintaining a part of the outer convolution of the tape line in contact with the angle-shaped portion of the rim flange at a point in proximity to the opening in the circular portion of the rim flange.
9. In a tape measure a case provided with a rim, and a flexible extension secured within the case and constituting a guide for a flexible tape line, said extension having inherent means for maintaining the tape line in engagement with a portion of the rim and further for maintaining the major portion of the extension in spaced relation with respect to the tape line.
10. In a tape measure a case including spaced side walls, one of said walls provided with an angular flange to constitute a rim, the other of said walls provided with an angular flange enclosed by and positioned against said rim flange, and an integral resilient extension projecting from one end of said enclosed flange and having its free terminal engaging with the other end of said enclosed flange, that portion of said extension between the ends of said enclosed flange extended across the inner surface of the side walls of the case and movable independently thereof.
11. In a tape measure a case provided with a rim, a flexible member forming an extension of the rim and supported within the case and arranged in spaced relation with respect to the rim to accommodate a flexible tape line, said extension and rim each provided with an opening for the passage of the tape line, that portion of the latter between said opening arranged between the rim and extension, said rim provided with an elongated slot for exposing the tape line, and an indicator at one of the walls of said slot to register linear measurements on the tape line.

In testimony whereof I affix my signature hereto.

CHARLES W. CROGAN.
